REFRIGERATION

Curtis C. Coons, North Canton, and William H. Kitto, Canton, Ohio, assignors to The Hoover Company, North Canton, Ohio, a corporation of Ohio

Application July 20, 1938, Serial No. 220,188
In Great Britain August 20, 1937

17 Claims. (Cl. 62—119.5)

This invention relates to refrigerating systems and more particularly to evaporator structures for such systems.

In refrigerating systems as heretofore constructed, the refrigerating fluid flowed downwardly through the evaporator by gravity. We have discovered an entirely new principle of evaporation wherein the refrigerant fluid is caused to circulate upwardly through the evaporator against the force of gravity by the energy supplied from a propelled stream of inert gas flowing through the evaporator. The broad aspects of this principle are disclosed and claimed in our co-pending application, Serial No. 220,189 filed July 20, 1938.

While it is possible to drag or sweep the liquid refrigerant through the evaporator from the lowest to the highest points thereof, it is not always desirable to do so. It may be desirable to use evaporator conduits of such diameter that the inert gas stream will not flow therethrough with a velocity high enough to drag or sweep the liquid refrigerant along therewith; the height of the evaporator may be so great that the gas circulating through the evaporator-absorber system is not placed under sufficient pressure to lift the liquid refrigerant entirely through the evaporator; the inert gas may be too light to elevate the liquid through the full height of the evaporator; and with some systems it may be desirable to extend the evaporator below the condenser and to connect the two by a short direct connection.

We have further discovered that a refrigerating system embodying an evaporator in which the liquid is dragged or swept through the system by a propelled stream of inert gas is self-regulating for atmospheric temperature changes. That is, the system automatically regulates itself to compensate for changes induced therein by variations in atmospheric temperature conditions, thus dispensing with complex and cumbersome auxiliary equipment for compensating the system for changes in atmospheric temperature changes.

An evaporator in which the liquid refrigerant is dragged or swept therethrough by a propelled stream of inert gas is well adapted to multi-temperature operation. More specifically, an evaporator in which the inert gas drags or sweeps the liquid upwardly therethrough automatically adapts itself to a structure having a low temperature freezing section and a higher temperature box-cooling section.

Previous three fluid absorption refrigerating

systems which are controlled by a cycling control have the disadvantage that there is a time lag between energization of the boiler heater and the circulating fan and the production of refrigeration; this is due to the time required to bring the boiler up to a boiling temperature. Our present evaporator automatically overcomes this difficulty by storing refrigerant liquid between active cycles whereby to produce refrigeration immediately the circulating fan is energized.

The principles above discussed are capable of expression in various structures. This application is concerned primarily with structures in which the liquid refrigerant is supplied to an intermediate evaporator level from which point the liquid is elevated through the evaporator to the top thereof and is then drained to the bottom of the evaporator.

Other objects and advantages of the invention will become apparent as the description proceeds when taken in connection with the accompanying drawing in which:

The single figure represents a diagrammatic illustration of a three fluid refrigerating system having the evaporator thereof shown in perspective and on an enlarged scale.

We have illustrated our invention as applied to a continuous three fluid absorption refrigerating system comprising a boiler B, an analyzer D, a rectifier R, an air-cooled condenser C, an evaporator E, an air-cooled absorber A, and a pressure equalizing medium circulating fan F driven by an electrical motor G. With the exception of the evaporator E, all elements of this system are illustrated diagrammatically, it being understood that they may be of any specific construction or form desired.

The elements just described are suitably connected by various conduits to form a plurality of gas and liquid circuits. It will be understood that the system is suitably charged with a refrigerant, such as ammonia, an absorbent, such as water, and a pressure equalizing medium, preferably a dense inert gas such as nitrogen. The boiler B is heated in any suitable manner as by a gas burner or an electric cartridge heater, it being understood that the source of heat to the boiler and the electrical motor G are controlled in any suitable or approved manner. A suitable control mechanism is disclosed in the co-pending application of Curtis C. Coons, filed June 17, 1937, Serial No. 148,424.

Refrigerant vapor generated by the application

55 of heat to the solution of refrigerant and ab-

sorbent contained in the boiler B passes upwardly through the analyzer D in counterflow to strong liquor supplied thereto from a source to be described hereinafter whereby the refrigerant vapor is substantially freed of vapor of absorption liquid. Refrigerant vapor is conveyed from the analyzer D to the condenser C by way of a conduit 11. An air-cooled rectifier R, which is included in the conduit 11, causes condensation of any vapor of absorption solution which may pass through the analyzer D. The refrigerant vapor is liquefied in the condenser C, which extends well below the top portion of the evaporator, preferably by heat exchange with the surrounding air, and is discharged therefrom through a conduit 12 leading to the evaporator.

The exact operation of the evaporator will be explained in detail hereinafter. For the present it is sufficient to note that the liquid refrigerant is discharged into the evaporator through the conduit 12 and evaporates into a propelled stream of inert gas to produce refrigeration. The mixture of inert gas and refrigerant vapor produced in the evaporator is discharged from the box-cooling section 13 thereof into the inner conduit 14 of a gas heat exchanger 15. The conduit 14 communicates with the lower end of a tubular air-cooled absorber A. The inert gas refrigerant vapor mixture passes upwardly through the absorber A in counterflow to absorption liquid flowing downwardly therethrough whereby the refrigerant vapor is separated from the inert gas by absorption. The inert gas is discharged from the absorber A into the suction inlet of the circulating fan F through a conduit 16. The fan places the inert gas under pressure and discharges it through a conduit 17 into the outer path of the gas heat exchanger 15 from which it is returned to the evaporator through a conduit 18.

The weak liquor formed in the boiler by the generation of refrigerant vapor is conveyed therefrom to the upper end of the absorber A through a conduit 20 which in part forms the inner member of a liquid heat exchanger 21. The weak absorption solution flows downwardly through the absorber A in counterflow to the inert gas refrigerant vapor mixture passing upwardly therethrough whereby to produce strong absorption solution. The strong solution flows to the low point of the conduit 14 from which it is drained by a conduit 22 into a strong solution reservoir 23. The strong solution is conveyed from the reservoir 23 to the liquid heat exchanger 21 by a conduit 24. A conduit 25 conveys strong solution from the liquid heat exchanger 21 into the analyzer D.

The absorber A is at an elevation higher than the boiler-analyzer system B—D wherefore the weak liquor en route to the upper end of the absorber A must be elevated thereto. A conduit 27 is connected to the gas discharge conduit 17 of the fan F and to the conduit 20 below the liquid level in the boiler-analyzer system whereby the weak solution is elevated through the conduit 20 into the upper end of the absorber by gas-lift action.

Referring now to the evaporator E in detail, it will be seen that it comprises a coil section 29 constituting a low temperature or ice-freezing section and a high temperature box-cooling section 13 provided with a plurality of air-cooling fins 31. It will be seen also that the box-cooling conduit 13 is considerably larger in diameter than the coil section 29.

As illustrated, the coil section 29 of our evap-

orator comprises a plurality of parallel coil sections positioned in vertically spaced horizontal planes. Each coil section comprises a pair of U-shaped elements whereby it is made up of a pair of outer legs and a pair of inner legs, all spaced substantially equal distances apart. The U-shaped portions of each coil section are serially connected together by a conduit extending across the rear of the evaporator and connecting the outer leg elements thereof. The inner legs of the U-shaped portions of each coil section form the inlet and outlet connections thereof. One inner leg element of the lowest coil section forms the inlet thereof, and the other inner leg element of the lowest coil section is connected to the superposed inner leg element of the superposed coil section. This process is continued for as many coil sections as may be desired, until the section subjacent the top coil section is reached. The top coil section is provided with but one inner leg element; the other leg element thereof is replaced by an elevated enlarged conduit forming a box-cooling coil. The inner leg element of the top coil section is connected to the subjacent inner leg element of the subjacent coil section. Thus it will be seen that our evaporator may be formed of a single tube bent into the desired shape whereby to form a plurality of serially connected coil elements forming shelves in vertically spaced horizontal planes.

The evaporator will now be described in detail with respect to the accompanying drawing and the reference characters marked thereon. For purposes of convenience, the description will proceed with respect to the direction of inert gas flow through the evaporator. It has previously been noted that inert gas is led into the evaporator through the conduit 18. The conduit 18 opens into one inner leg 32 of the bottom coil section 30. The inert gas passes through the coil section 30 and is discharged therefrom through the other inner leg 33 into the riser conduit 34 which communicates with an inner leg 35 of the central coil section 36. The inert gas passes through the central coil section 36 and is discharged therefrom through the inner leg element 38 into the riser conduit 39 which opens into the inner leg element 40 of the top coil 41. The inert gas is discharged into the box-cooling conduit 13 through the riser conduit 42 after passing through the top coil section 41. The inert gas then passes rearwardly through the large diameter box-cooling conduit 13 to the gas heat exchanger 15.

Liquid refrigerant is supplied through the condenser discharge conduit 12 into the central portion of the rear cross connecting conduit 37 of the central coil section 36.

The coil sections 30 and 36 form convenient shell supports whereby the evaporator may be readily enclosed in a casing with trays or tray supporting shelves resting on these coil sections.

A U-shaped drain conduit 50 is connected between the discharge end of the box-cooling conduit 13 and the inlet portion of the leg element 35 of the central coil section 36. It will be noted that the drain conduit 50 extends downwardly in the rear of the cross connecting conduits of the coil sections and below the lowest coil section from which position it curves upwardly to join the element 35. The leg portions of a small diameter U-shaped conduit 52 are connected to the conduits 18 and 50 a slight distance above the plane of the lowest coil section 30.

A drain conduit 55 extends between the strong liquor line 24 and the leg element 33 adjacent

the riser conduit 34. This drain relieves the bottom coil section 30 of excess liquid refrigerant and allows foreign bodies to escape from the evaporator coils. Foreign bodies, such as absorption solution, which reach the evaporator from the condenser are circulated through the evaporator with the liquid refrigerant and into the drain 55.

In order to describe the operation of the machine, it will be assumed that it has not been operating and that the evaporator is warm. The control mechanism will energize the motor G and the heater for the boiler B. Liquid refrigerant will discharge into the conduit 37 from the pipe 12 shortly after heat is applied to the boiler B. The inert gas supplied to the conduit 18 will pass through the evaporator, but it will also by-pass through the conduits 50 and 52, as a result of which the velocity of the gas passing through the coil sections 30, 36 and 41 is low. The liquid refrigerant will spread through the coil section 36 in both directions from the conduit 12. After a short period of time liquid refrigerant will begin to flow downwardly into the U-shaped portion of the conduit 50 and will eventually block that conduit. The liquid will continue to accumulate in the conduit 50 until it overflows through the U-shaped conduit 52 into the inert gas inlet conduit 18. At this time the conduits 50 and 52 will be blocked and the inert gas will cease to by-pass therethrough. The velocity of the inert gas flowing through the coil sections will reach a high value as soon as the conduits 50 and 52 are blocked. Inert gas passing through the central coil section 36 will now sweep the liquid refrigerant supplied thereto along with it to the riser conduit 39. A finely divided body of liquid refrigerant will be supported in the riser conduit 39 by the inert gas stream which will blast or sweep its way therethrough in a continuous stream. The frictional drag and impact of the gas will carry part of the liquid upwardly into coil section 41.

The inert gas will then propel the liquid refrigerant through the upper coil section 41 and through the elevating conduit 42 into the box-cooling conduit 13. The box-cooling conduit 13 is preferably inclined slightly downwardly from front to rear whereby the liquid refrigerant blown thereinto may flow along the bottom thereof by gravity. Any liquid refrigerant not evaporated at the end of the box-cooling conduit 13 is drained therefrom into the conduit 50 and through the conduit 52 into the inert gas inlet conduit 18. Liquid refrigerant supplied to the inert gas inlet conduit 18 is carried along by the inert gas stream through the lower coil section to the riser conduit 34.

In order to produce refrigeration efficiently and at the temperatures necessary to freeze ice and to preserve foodstuffs in domestic refrigerating cabinets, it has been found advantageous to circulate the inert gas through the evaporator under conditions such that the volume of the inert gas will be several hundred times the volume of liquid refrigerant supplied to the evaporator per unit of time. Consequently, the velocity of flow of the inert gas through the evaporator will be materially greater than the velocity of flow of the liquid refrigerant. This evaporator meets that condition ideally while circulating the liquid refrigerant upwardly through all portions of the evaporator. Several factors have a material bearing on the design of an apparatus which

will produce the desired conditions. The lifting power of the inert gas stream is a function of its density, pressure, and velocity of flow through the evaporator. In general, an increase in the value of any one or more of the above enumerated factors results in an increase in the lifting power of the inert gas. Other things being equal, the velocity of the inert gas will be a function of the effective cross-sectional area of its path of flow; an increase in effective cross-sectional area of that path resulting in a decrease in gas velocity. For example, it has been found that a propelled stream of nitrogen will circulate liquid ammonia upwardly through an evaporator constructed of approximately one-half inch inside diameter tubing and having a vertical height of approximately ten inches, a pressure differential of between two and four inches of water between the gas inlet and outlet connections to the evaporator, and with the total system pressure ranging between 270 and 400 pounds per square inch. The above dimensions are cited by way of example only and are not limiting in any sense.

It has been observed in the operation of this type of evaporator that it frosts evenly throughout including the pipe section 35 and the outer right hand conduit of the central evaporator coil section 36. It is not definitely known whether refrigeration is produced in these portions of the evaporator by liquid refrigerant flowing counter to the inert gas stream backwardly toward the connection of the drain conduit 50, or by liquid carried up into that conduit from the leg section 33 of the lowest coil section through the riser conduit 34, or merely by the very cold inert gas stream passing therethrough.

If desired, a small dam 60 may be placed in the leg portion 35 of the central coil section 36 adjacent the point of connection between the drain conduit 50 and the leg element 35. This dam functions to collect a quantity of liquid refrigerant when the machine is first started and it also functions to collect liquid in the evaporator and liquid discharged through the conduit 12 after the motor G has been de-energized. Without the dam 60 this liquid would merely be wasted through the drain system. When the control mechanism re-energizes the boiler heater and the circulating fan, a quantity of liquid will be present in the evaporator to produce refrigeration during the interval between re-energization of the system and the time at which the boiler-condenser system comes into full operation.

It will be seen from the description and drawing that liquid refrigerant is supplied first to the central coil section 36 and that lean inert gas is supplied to the bottom coil section 30. The coil sections 30 and 36 carry the main freezing load because the ice trays will rest thereon; hence it is desirable that they operate at low temperatures. The evaporator is designed in such fashion that the coil sections 30 and 36 will operate at very low temperatures. It is apparent that the inert gas stream passing through the riser conduit 39 will be relatively rich due to evaporation which has occurred in the coil sections 30 and 36. Because of the relatively high vapor pressure of the refrigerant in the inert gas stream passing into conduit 40, evaporation will occur in the coil section 41 at a temperature higher than those prevailing in the coil sections 30 and 36, which will further increase the vapor pressure of the ammonia in the inert gas stream whereby any evaporation

occurring in the box-cooling conduit 13 will be at a still higher temperature. Preferably the box-cooling conduit 13 and the fins 31 thereon are designed in such fashion that the surfaces of all elements exposed to the air operate at temperatures sufficiently high to prevent or minimize frost deposition.

It is to be noted that only a portion of the refrigerant liquid ever reaches the lowest coil section. This aids in regulating the temperature ranges in the various coil sections for the very lean gas in the lowest coil section is normally supplied with only enough refrigerant to produce the desired amount of refrigeration whereby to prevent excessively low temperatures in the lowest coil section. The gas reaching the coil section 36 is sufficiently rich in refrigerant vapor to prevent excessive evaporation of the large quantity of liquid supplied to that coil section.

From the description it will be seen that our evaporator and gas inlet conduit may conveniently be made of a single tube bent to the proper shape and welded to the gas heat exchanger and the box-cooling conduit 13. Preferably the box-cooling conduit 13 is reduced in diameter immediately beyond its point of connection with the drain conduit 50 whereby to facilitate drainage through the conduit 50.

We have provided a refrigerating system in which a positively propelled stream of inert gas travels through the evaporator at a pressure slightly above that generally prevailing within the system and at a sufficiently high velocity to sweep or carry liquid refrigerant along with the inert gas stream and to elevate it a substantial distance through portions of the evaporator.

The liquid in the evaporator has a throttling effect on the inert gas passing therethrough. This is very useful as it provides a fully automatic regulating system for the flow of inert gas through the evaporator. The flow of gas need not be as high at low room temperatures as at high room temperatures because of the higher purity of the inert gas stream leaving the absorber at low room temperature. However, at low room temperatures the pressure within the system drops whereby the fan generates a lower pressure, hence, at low room temperatures the throttling effect of the liquid in the evaporator is greater and the flow of inert gas is thus automatically regulated to the amount necessary to produce most efficient operation under existing conditions.

The action of the inert gas on the liquid refrigerant may be briefly described as follows: In substantially horizontal conduits the gas stream flows over a stream of liquid in the bottom portion of the conduit to which it imparts a propelling force by the frictional drag of the gas stream as it passes over the liquid. Additionally, the dragging action of the gas on the liquid serves to agitate the liquid stream which improves the gas and liquid contact therebetween and aids the evaporation process. In the elevating or rising conduits, the gas stream supports a body of liquid in a divided state through which the gas continuously forces itself agitating such body of liquid and blowing or dragging a portion thereof into the next evaporator conduit. Though the 70 gas is described herein as travelling at a high velocity, this term is to be understood in a relative sense because the velocity of the gas will depend upon the conditions prevailing in the particular system as noted above; for example, in

the particular embodiment of the invention disclosed herein, the velocity of gas flow through the evaporator is of the order of a few feet per second if a dense gas, such as nitrogen, is utilized.

The flow of inert gas through the evaporator is substantially continuous and steady though there is a pressure gradient from the inlet to the outlet portions thereof due to the throttling action of the liquid, particularly in rising conduits, on the gas stream. This insures substantially continuous uniform propulsion of liquid through the evaporator and continuous production of refrigeration whenever the refrigerating mechanism is operating.

While we have illustrated and described a particular embodiment of our invention, it is not limited thereto but is capable of embodiment in other constructional forms and variations without departing from the spirit of the invention or the scope of the appended claims.

We claim:

1. An evaporator adapted for use in absorption refrigerating apparatus comprising a plurality of serially connected coil sections positioned in vertically spaced horizontal planes, a gas inlet connection to the lowest of said sections and a gas outlet connection to the highest of said sections, a refrigerant supply pipe connected to an intermediate one of said coil sections, a drain conduit extending to a level below said lowest coil section and connected between the gas outlet of said uppermost coil section and said intermediate coil section, and means connecting said drain to the gas inlet of said lowermost coil portion.

2. An evaporator for refrigerating systems comprising a plurality of serially connected coil sections positioned in vertically spaced horizontal planes, a finned box-cooling section positioned above said coil sections and serially connected thereto, means for supplying an inert gas to the lowest of said coil section and for removing inert gas from said box-cooling section the highest one of said coil sections comprising a U-shaped conduit element connected to the inlet of said box-cooling section by means of a substantially L-shaped conduit, the lower ones of said coil sections each comprising a pair of U-shaped portions having the outer legs of the U serially connected together and the inner legs of the U forming the inlet and outlet connections thereof, a drain conduit extending below said lowermost coil section and connected between the gas outlet portion of said box-cooling section and the inlet of one of said intermediate sections, and means connecting said drain through a trap to the gas inlet portion of said lowermost coil section.

3. Refrigerating apparatus comprising a boiler, a condenser, an absorber, an upstanding evaporator, means for conveying refrigerant vapor from said boiler to said condenser, means for supplying liquid refrigerant from said condenser to the central portion of said evaporator, means interconnecting said evaporator and said absorber to form a pressure equalizing medium circuit, means for propelling a pressure equalizing medium through said circuit, said circuit being arranged to supply pressure equalizing medium under pressure to the lower portion of said evaporator and to circulate the same through said evaporator with sufficient velocity to propel the refrigerant through said evaporator, and means for draining liquid refrigerant elevated through said evaporator from the gas outlet thereof to the

lowest section thereof without allowing the pressure equalizing medium to flow therethrough.

4. A refrigerating system comprising a solution circuit including a boiler and an absorber, a pressure equalizing medium circuit including a vertically extending evaporator and said absorber, power-driven means for propelling a dense pressure equalizing medium through said pressure equalizing medium circuit, a refrigerant vapor liquefying means connected to said boiler and to an intermediate portion of said evaporator, and means including a liquid seal interconnecting the top and bottom portions of said evaporator, the arrangement being such that liquid refrigerant travels upwardly through said evaporator and is then conveyed to the bottom of said evaporator through said means including a liquid seal.

5. An absorption refrigerating system including a source of refrigerant vapor, means for liquefying the vapor, an evaporator connected to receive liquid refrigerant from said liquefying means intermediate the top and bottom thereof, means for supplying a propelled dense inert gas to the bottom portion of said evaporator, means for conveying inert gas and refrigerant vapor from the top of said evaporator, means for conveying liquid refrigerant from the top of said evaporator to the bottom thereof, and means for draining excess liquid from the bottom of said evaporator to another part of said system.

6. An evaporator comprising a plurality of vertically spaced sections, means for propelling a dense inert gas through said sections from the bottom to the top thereof, means for supplying liquid refrigerant to an intermediate section of said evaporator, means for draining liquid refrigerant from the top to the bottom of said evaporator, a dam in said evaporator constructed and arranged to impede liquid draining to the bottom thereof from said intermediate section, and a drain connected to the lowest section of said evaporator.

7. An absorption refrigerating apparatus including an inert gas circuit including an upstanding evaporator and an absorber, a solution circuit including a boiler and said absorber, means for liquefying refrigerant vapor generated in said boiler and for supplying the same to an intermediate portion of said evaporator, means for propelling the inert gas upwardly through said evaporator with sufficient force to propel liquid refrigerant therethrough, and means for conveying unevaporated liquid refrigerant from the upper to the lower portion of said evaporator.

8. An absorption refrigerating apparatus including an inert gas circuit including an upstanding evaporator and an absorber, a solution circuit including a boiler and said absorber, a condenser extending below the upper portion of said evaporator connected to receive refrigerant vapor from said boiler and to discharge liquid refrigerant to an intermediate portion of said evaporator, means for propelling the inert gas through said evaporator with sufficient force to propel liquid refrigerant therethrough, and means for conveying unevaporated liquid refrigerant from the upper to the lower portion of said evaporator.

9. An absorption refrigerating apparatus including an inert gas circuit including an upstanding evaporator and an absorber, a solution circuit including a boiler and said absorber, means for liquefying refrigerant vapor generated in said boiler and for supplying the same to an

intermediate portion of said evaporator, means for propelling the inert gas upwardly through said evaporator with sufficient force to propel liquid refrigerant therethrough, and means for conveying unevaporated liquid refrigerant from the upper to the lower portion of said evaporator, said last mentioned means including means for preventing the passage of inert gas therethrough.

10. Absorption refrigerating apparatus comprising an evaporating element in which refrigeration is produced by the evaporation of a refrigerant liquid into a pressure equalizing medium, an absorbing element in which refrigerant vapor is absorbed in an absorbing liquid from a pressure equalizing medium, means connecting said element to form a pressure equalizing medium circuit, one of such elements including a plurality of vertically spaced serially connected sections, a liquid supply means connected to an intermediate one of such sections, means including a liquid trapping gas flow preventing seal for draining liquid from one of said sections located at an elevation above said intermediate section to one of said sections located at an elevation below said intermediate section, and means in said pressure equalizing medium circuit for propelling the pressure equalizing medium upwardly through said one element under sufficient pressure and velocity to distribute the liquid therethrough.

11. Absorption refrigerating apparatus comprising an inert gas circuit including a plurality of elements in which a vapor exchange occurs between a liquid and an inert gas, one of said elements including a plurality of serially connected portions positioned at different elevations, means for supplying a liquid to one of said portions which is positioned at an intermediate elevation, means for draining liquid from one of said portions which is at an elevation above said intermediate portion to another of said portions which is at an elevation below said intermediate portion, and means in said inert gas circuit for propelling inert gas upwardly through said serially connected portions with a velocity sufficient to circulate the liquid therethrough by the frictional drag exerted on the liquid by the inert gas.

12. Absorption refrigerating apparatus comprising an inert gas circuit including a plurality of elements in which a vapor exchange occurs between a liquid and an inert gas, one of said elements including a plurality of serially connected portions positioned at different elevations, means for supplying a liquid to one of said portions which is positioned at an intermediate elevation, liquid draining means extending downwardly below said intermediate portion to form a gas flow preventing liquid trap connecting the highest of said portions and said intermediate portion, means including a gas flow preventing liquid trap for conveying liquid from said liquid draining means to the lowest of said portions without emptying said first-mentioned gas flow preventing liquid trap, and means in said inert gas circuit for circulating inert gas upwardly through said portions under sufficient pressure to elevate the liquid therethrough by the propelling force of the inert gas.

13. Absorption refrigerating apparatus comprising an inert gas circuit including a plurality of elements in which a vapor exchange occurs between a liquid and an inert gas, one of said elements including a plurality of serially connected portions positioned at different elevations, means

for supplying a liquid to one of said portions which is positioned at an intermediate elevation, means arranged to conduct liquid without allowing a flow of gas from the highest of said portions to the lowest of said portions, and means in said inert gas circuit for circulating inert gas upwardly through said serially connected portions with sufficient pressure and velocity to distribute the liquid therethrough and to pass into and out of the liquid as a vapor exchange occurs between the liquid and the inert gas.

14. Absorption refrigerating apparatus comprising an inert gas circuit including a plurality of elements in which a vapor exchange occurs between a liquid and an inert gas, one of said elements including a plurality of serially connected portions positioned at different elevations, means for supplying a liquid to one of said portions which is positioned at an intermediate elevation, means arranged to conduct liquid without allowing a flow of gas from the highest of said portions to the lowest of said portions, means for removing liquid from a portion of said element which is located at an elevation below said intermediate portion, and means in said inert gas circuit for circulating inert gas upwardly through said serially connected portions with sufficient pressure and velocity to distribute the liquid therethrough as a vapor exchange occurs between the liquid and the inert gas.

15. Refrigerating apparatus comprising an evaporator, including a plurality of vertically spaced sections, riser conduits serially connecting adjacent vertically spaced sections, means for supplying liquid refrigerant to an intermediate section of said evaporator, means for supplying inert gas to the lowest of said evaporator sections

and for propelling the inert gas upwardly through said evaporator sections with sufficient force to elevate liquid refrigerant therethrough, and means for draining refrigerant carried to the inert gas outlet of the highest of said sections to the inert gas inlet of the lowest of said sections.

16. Absorption refrigerating apparatus comprising an evaporator including a plurality of vertically spaced sections, means serially connecting said sections, means for supplying liquid refrigerant to an intermediate portion of said evaporator, means for supplying a dense inert gas to the lowest of said evaporator sections and for propelling the inert gas upwardly through said evaporator sections with sufficient force to elevate liquid refrigerant therethrough, means for draining liquid refrigerant from the highest of said sections to the lowest thereof, said last mentioned means being constructed and arranged to cause the same to be sealed against the passage of gas by the refrigerant flowing therethrough.

17. Absorption refrigerating apparatus including an evaporator, means for supplying liquid refrigerant to an intermediate portion of said evaporator, means for supplying a dense inert gas to the lowest of said evaporator sections and for propelling the inert gas upwardly through said evaporator sections with sufficient force to elevate liquid refrigerant therethrough, means for conveying liquid refrigerant from the top portion of said evaporator to the lowest portion thereof, said last mentioned means being constructed and arranged to prevent passage of inert gas therethrough during normal operation.
